US00D915831S

(12) **United States Design Patent** (10) Patent No.: **US D915,831 S**
Seiders et al. (45) Date of Patent: **** Apr. 13, 2021**

(54) **CONTAINER**

(71) Applicant: **YETI Coolers, LLC**, Austin, TX (US)

(72) Inventors: **Roy Joseph Seiders**, Austin, TX (US); **James William Sonntag**, Austin, TX (US); **Christopher M. Keller**, Austin, TX (US); **Steve Charles Nichols**, Austin, TX (US)

(73) Assignee: **YETI Coolers, LLC**, Austin, TX (US)

(**) Term: **15 Years**

(21) Appl. No.: **29/738,992**

(22) Filed: **Jun. 22, 2020**

Related U.S. Application Data

(63) Continuation of application No. 29/673,008, filed on Dec. 11, 2018, now Pat. No. Des. 887,789, which is (Continued)

(51) **LOC (13) Cl.** **07-01**

(52) **U.S. Cl.**

USPC **D7/605**

(58) **Field of Classification Search**

(57) **CLAIM**

The ornamental design for a container, as shown and described.

DESCRIPTION

FIG. 1 is a top, front, right perspective view of a container showing our new design;

FIG. 2 is a front view thereof;

FIG. 3 is a rear view thereof;

FIG. 4 is a left side view thereof;

FIG. 5 is a right side view thereof; and,

FIG. 6 is a top view thereof.

The broken lines form no part of the claimed design.

1 Claim, 6 Drawing Sheets

Related U.S. Application Data

a continuation of application No. 29/610,438, filed on Jul. 12, 2017, now Pat. No. Des. 835,470.
